UNITED STATES PATENT OFFICE.

JOHN HERBERT TOAL, OF CHICAGO, ILLINOIS.

SAFETY-RAZOR.

1,259,931.

Specification of Letters Patent. Patented Mar. 19, 1918.

Application filed May 8, 1916. Serial No. 96,037.

To all whom it may concern:

Be it known that I, JOHN HERBERT TOAL, a citizen of the United States of America, and resident of Chicago, Cook county, Illinois, have invented a certain new and useful Improvement in Safety-Razors, of which the following is a specification.

My invention relates to safety razors of that particular kind in which the blade and handle are like those of an ordinary razor, or substantially so, and in which a removable guard is applied to the blade.

The object of my invention is to provide an improved construction and arrangement whereby the said guard is reversible, thereby to permit use thereof on either side of the blade.

Another object is to provide an improved construction and arrangement whereby the guard is held securely in place at the outer end of the blade, and whereby, with a two-edged blade having a longitudinal ridge extending midway between the two edges, it will not be necessary to use devices heretofore considered necessary for holding the guard against lateral displacement.

Another object is to provide an improved construction and arrangement whereby the guard is held more firmly and securely against endwise displacement from the blade.

To these and other useful ends, my invention consists in matters hereinafter set forth and claimed.

In the accompanying drawings:

Fig. 1 is a side elevation of a safety razor embodying the principles of my invention, showing the guard in place on the blade.

Fig. 2 is a similar view showing the opposite side of the razor.

Fig. 3 is an enlarged detail section on line 3—3 in Fig. 1, showing a portion of the blade and guard broken away between the ends thereof for convenience of illustration.

Fig. 4 is an enlarged cross-section on line 4—4 in Fig. 1.

Fig. 5 is a face view of one side of the outer end portion of the blade.

Fig. 6 is a detail view showing another method of holding the guard on the stem or tang of the blade.

As thus illustrated, my invention comprises a blade A having opposite edges *a*, and having a longitudinal center ridge 1 on each surface thereof, these ridges being formed, it will be seen, by the grinding of

the blade—that is to say, the blade is hollow-ground on each side thereof, and the two shallow and longitudinal grooves thus formed on each surface of the blade provide the said ridge between them. At its outer end, the said blade is provided on either side thereof with a transverse depression or cross-groove 2, formed in any suitable manner, so that the blade is thicker at the end than between the bottoms of the two depressions. The other end of the blade is provided with the usual stem or tang 3 of any suitable shape.

The guard B is formed from sheet-metal of suitable stiffness, being provided on each edge thereof with teeth *b* of the usual form and character, and which teeth extend slightly beyond the edges of the blade for the well-known purpose. The outer end of this guard is provided with a clamping jaw or resilient lug 4 to engage the grooves or depressions 2, it being observed that the portion of the guard directly under this jaw is depressed or bent at 5, whereby the portions 4 and 5 engage the said grooves or depressions at opposite sides of the blade. In cross-section (see Fig. 4.), the guard is shaped to conform to the surface of the blade, being provided with a groove 6 to tightly and accurately fit the ridges 1, whereby the guard is held against lateral displacement when on the blade, the clamping jaw 4 and the coöperating portion 5 merely holding the guard against endwise displacement from the blade. The other end of said guard is formed with a stem or tang 6 having a notch 7 which receives the double-headed rivet 9 inserted through the tang or stem of the blade, whereby the guard is held firmly against lateral displacement at this end. The said rivet can be composed of two parts, if desired, these two parts being forced into an opening in the tang of the razor blade and thus held therein. Obviously, however, this rivet, or the two sections of the rivet, can be secured to the blade in any suitable manner.

If desired (see Fig. 6.), a slide C can be used on the tang or stem of the blade to slide over the stem or tang 6 of the guard.

With either construction, however, the guard can be reversed and used on either side of the blade, so that either surface of the blade can be exposed and used for shaving.

A handle D, of any suitable character, is

pivoted at *d* to the tang or shank of the blade, so that the razor blade and its guard will fold within said handle, in the manner of an ordinary razor. Thus the razor can be used either with or without the guard, and the latter can be used on either side of the blade. Without the guard, the blade and handle form a complete ordinary razor. By ordinary, I mean the old and common 10 form of razor having a solid or thick blade and a handle at one end thereof.

The blade *A*, as shown, and as described, has the same formation on both sides thereof, being what is ordinarily known as a hollow-ground blade, so that in cross-section each side has two concave curves. The guard *B*, therefore, in cross-section, has two convex curves to fit the concave curves of the blade, so that the guard is held by either 15 ridge 1 against lateral displacement, but is at the same time removable from the blade by slight outward endwise movement thereof away from the handle. When the guard is forcibly moved endwise, away from the 20 handle, the flexible lug 4 rises out of the depression 2 (at either side of the blade), thus permitting complete detachment of the 25 guard from the blade.

What I claim as my invention is:—

30 1. A two-edged razor blade hollow-ground on each side to provide two ridges and having an integral shank at one end thereof, a handle secured to said shank, so that said blade and handle can be used as an ordinary two-edged razor, and a two-edged guard which in cross-section has two convex curves to fit the concave curves of either side of said blade, so that either ridge will hold the 35 guard against lateral displacement, and 40 which guard is attachable directly to opposite ends of said blade at either side thereof to convert said ordinary razor into a two-edged safety razor having said guard reversible from one side of the blade to the other, said guard being detachable by endwise movement for a short portion of the 45 length thereof in direct contact with either side of the blade.

2. A two-edged razor blade having an 50 integral shank, a handle secured to said shank, so that said blade and handle can be used as an ordinary two-edged razor, a two-edged guard which is attachable directly to opposite ends of said blade at either side thereof to convert said ordinary razor into a two-edged safety razor having said guard reversible from one side of the blade to the other, said blade having its end provided with 55 depressions at opposite sides thereof, said shank having external attaching means, the middle portion of said blade being thickened to form two opposite longitudinal ridges, said guard being formed to fit either of said 60

ridges, a lug on said guard to engage in either of said depressions, and an extension 65 on said guard to engage said means at either side of said shank, said lug being held against lateral displacement in said depressions by the adjacent engagement of said ridges with said guard. 70

3. A two-edged razor-blade having an integral shank, a handle secured to said shank, so that said blade and handle can be used as an ordinary two-edged razor, a two-edged guard which is attachable directly to opposite ends of said blade to convert said ordinary razor into a two-edged safety-razor, 75 said blade having its end provided with a transverse depression, said shank having external attaching means, the middle portion 80 of said blade being thickened to form a longitudinal ridge, said guard being formed to fit said ridge, a lug on said guard to extend over the blade and engage in said depression, said lug being flexible to rise out of said depression when said guard is forcibly moved endwise from the blade, and an extension of 85 said guard to engage said means on the shank, said depression being so formed that said lug is movable sidewise but held against 90 lateral displacement therein by the engagement of said ridge with said guard.

4. A two-edged razor blade having an integral shank, a handle secured to said shank, so that said blade and handle can be used as an ordinary two-edged razor, and a two-edged guard which is attachable to opposite ends of 95 said blade to convert said ordinary razor into a two-edged safety razor, said blade having a depression at the outer end thereof, and said guard having a resilient lug disposed in position to lift slightly as the end 100 of the blade is inserted thereunder and to then spring into said depression, so that the guard is held by said lug against endwise 105 displacement from the blade, and said lug being flexible to rise out of said depression when the guard is forcibly moved endwise from the blade.

5. A razor blade having its outer end portion formed with depressions at opposite sides thereof, so that the blade is thicker at the end than between the bottoms of said depressions, and a guard having its outer end provided with oppositely arranged portions 115 to enter said depressions, one of said portions being a resilient lug adapted to lift slightly as the end of the blade is inserted between the two portions and to then spring into the depression, and said lug being flexible to rise out of said depression when the guard is forcibly moved endwise from the blade. 120

Signed by me at Chicago, Illinois, this 28th day of April, 1916.

JOHN HERBERT TOAL.
